GAME

Frank M. Clement, Chicago, Ill.

Application June 20, 1940, Serial No. 341,526

4 Claims. (Cl. 273—104)

My invention relates to the game of quoits or "horseshoes," and one purpose of the invention is to provide means to replace the usual clay padding now employed at the stake, which serves as a goal, and to substitute a more cleanly material which will prevent the quoits or shoes from becoming smeared with clay, and will eliminate flying dust and mud when the shoe lands at the stake. Another object is to provide a padding strong enough to withstand hard usage, particularly such as that experienced by game equipment used by the general public, as in parks and other places of amusement. A further object is to provide an improved surface, affording a non-skidding effect when the shoes or quoits land thereon so as to prevent them from bouncing or sliding away from scoring position. Other objects and advantages of the invention are particularly pointed out in the following specification. The invention comprises certain features and elements of construction in combination, as herein shown and described and as indicated by the claims.

In the drawing:

Fig. 1 is a perspective view of the box or platform together with the stake constituting the goal post, showing a horseshoe in scoring position at the stake, and including a protecting shield at the upper end of the latter but omitting the chain padding material which is a feature of this invention.

Fig. 2 is a vertical section taken fore and aft through the platform and stake, and showing one unit of the interlaced chain padding with the links extending into the vertical plane of the section.

Fig. 3 is a fragmentary sectional view of the pan or platform member with the chain padding thereon, and including a horseshoe resting on the padding.

Fig. 4 is a fragmentary end view of a securing strip and some of the chain links attached thereto.

Fig. 5 is a fragmentary side view of the securing strip showing a few links attached thereto, and indicating how the strip is riveted to the platform or pan.

The game of quoits is played either with specially formed rings, usually of steel, or with ordinary horseshoes or similarly shaped elements, also of steel. These playing pieces are tossed or thrown from a considerable distance toward a goal in the form of a post or stake, with the object of having them fall as close as possible to the stake, preferably encircling it for the highest

scores. When the game is played outdoors, the stake is usually driven into the ground, and where a regular playing court is provided, the earth may be in the nature of a fairly hard clay; but in either case the impact of the steel quoits or horseshoes rapidly breaks up the surface around the stake, raising considerable dust, and covering the quoits or horseshoes with dust, or mud if the ground is moist. The present invention provides improved equipment for such a game, including a plate or pan 1, preferably of metal, such as steel, provided with marginal flanges 2, 3, 4 and 5. The flange 5 at the side of the plate facing the player, is preferably a little lower than the other flanges, and the adjoining portions of flanges 3 and 4 are tapered at 6, as shown in Fig. 1. This diminishes the chance that the forward flange 5 or the corner portions at 6, 6, will be hit directly by a quoit or horseshoe during the progress of the game. The stake or goal post 31 is positioned at the center of the plate and secured rigidly by any suitable means, as for example, by welding it thereto, as indicated at 11 in Fig. 2. Preferably, a short section 25 of rubber hose or tubing 41 is fitted over the upper end of the stake to protect it and the shoes or quoits from injury. If desired, the stake may be set so as to lean slightly toward the forward side of the plate, that is, toward the flange 5 which faces the player so that the shoes or quoits striking the stake will tend to be deflected downwardly toward the platform instead of rebounding to a greater distance.

To receive the impact of the horseshoe or quoits 35 as they are thrown toward the stake 31, the entire upper surface of the plate 1 is covered with a steel padding preferably composed of short sections of chain anchored to the plate, but with several links extending from the point of anchorage 40 so that they may lie in a miscellaneous arrangement or mass overlapping each other more or less, and covering the plate surface. As shown, each section of chain includes an anchored link 7 with two links 8 and 9 engaged therewith and connected respectively to additional links 18 and 19. Fig. 5 shows only one link, 18, and one link, 19, but Fig. 2 indicates two additional connected links on each branch of the chain, extending from the anchored link 7. I find that about five 45 links in each branch are enough to provide a sufficiently flexible and extensive padding, which is indicated generally by the numeral 12, in Fig. 3. The anchored links 7 may be secured to the plate 50 in any convenient manner, and Figs. 2, 3 and 5 indicate a bent or corrugated strip of metal 15

secured by rivets to the upper surface of the plate 1 and thus forming a series of loops by which the links 7 are loosely held. It will be understood that a plurality of these strips 15 will be arranged preferably parallel, and side-by-side, over the entire surface of the plate 1, and that the short lengths of chain extending from them will overlie each other and overhang the flanges 2, 3, 4 and 5 so as to receive the impact of shoes or quoits thrown toward the goal post 31.

When the game is played according to standard regulations, the quoit or horseshoe is thrown toward the stake from a distance of about forty feet, traveling through the air and landing with considerable force, and with a tendency to skid or slide; but when a chain padding of the character just described is employed, the links on the upper surface of the padding are free to move in any direction and readily accommodate themselves to the shoe as it arrives, so that it tends to become slightly embedded in the padding, as shown in Fig. 3, without sliding or skidding after it lands. The sudden impact of the shoe against the free links of the padding not only forms a depression in them in which the shoe is lodged, but as some of the links are displaced in forming the depression the adjoining links are forced in various directions as a result of the displacement, and these links at the free ends of the chain sections tend to be more or less wrapped around the marginal portions of the shoes so as to prevent any skidding or sliding of the latter.

Incidentally, the mat of chain links protects the underlying plate 1 and all of its parts, from any direct or solid blow when the shoes or quoits are pitched, and thus avoids crystallization and consequent breakage of the plate and of the quoits themselves. And while a skillfully thrown horseshoe tends to land flatly, and without sliding, as indicated in Fig. 3, there are many instances in which the shoes strike the mat 12 edge-wise or in other positions so that they engage the links frictionally; which serves automatically to

polish and smooth the edges of the shoes, thereby eliminating the danger of steel slivers forming thereon and cutting the hands of the players.

Thus it will be seen that I have devised improved equipment for the game of quoits or horseshoes, particularly well adapted to use in public parks and other places of amusement, where the parts are subjected to severe service, and that this equipment not only improves the cleanliness of the game by eliminating dust and mud, but also tends to contribute to a more satisfactory action of the playing pieces in response to the skill of the players. I reserve the right to use any other suitable material, and to make such changes in construction and arrangement of the parts as properly fall within the spirit and scope of my invention, as indicated by the claims.

I claim:

1. A goal plate for a game of horseshoes or the like comprising a base overlaid with a loosely disposed mass of metallic chain links some of which are interlocked with each other and some of which are attached to the base.

2. A goal plate for a game of horseshoes or the like comprising a base overlaid with a mass of short lengths of metallic chain each attached by one link to the base, the ends of said lengths being unattached to the base and extending in miscellaneous arrangement thereover.

3. A goal plate for a game of horseshoes or the like comprising a metallic base having upstanding marginal flanges and overlaid with a loosely disposed mass of metallic chain links with some of said links overhanging and covering said flanges.

4. A goal plate for a game of horseshoes or the like comprising a metallic base and a plurality of relatively short lengths of chain each attached by one link to the base, said chains overlying the area of the base and overlapping each other, thus forming a metallic cushion to receive the shoes as they are pitched toward the goal.

FRANK M. CLEMENT.
